UNITED STATES PATENT OFFICE

SEWALL CABOT, OF BROOKLINE, MASSACHUSETTS.

CIRCUIT-CONTROLLER.

No. 917,749.

Specification of Letters Patent. Patented April 13, 1909.

Application filed November 10, 1908. Serial No. 461,926.

To all whom it may concern:

Be it known that I, SEWALL CABOT, a citizen of the United States, and a resident of Brookline, in the county of Norfolk and 5 State of Massachusetts, have invented a new and useful Improvement in Circuit-Controllers, of which the following is a specification.

My invention relates to circuit-controllers and more especially to devices for controlling 10 the operation of sonorous or persistently-oscillating circuits which are employed in space telegraphy and other arts for creating high frequency electrical oscillations. Heretofore the device most commonly employed 15 for controlling such circuits has been the spark-gap, consisting of two separated electrodes which are either stationary or relatively movable. When the electrical potential of the condenser reaches a sufficient 20 value to cause a disruptive discharge at the gap, the circuit becomes closed through a path of metal vapor between the electrodes allowing it to oscillate until the electrical energy has been dissipated in radiation or in 25 supplying heat to the spark-gap. It has long been recognized that a considerable amount of energy is lost in supplying heat to the spark-gap and that also under certain conditions it becomes difficult to clear away 30 the metal vapor between successive wave trains thus causing the potential at which disruptive discharge takes place to vary and impairing the quality of the sound of the spark as heard at the receiving system. 35 The production of this vapor furthermore at high powers also manifests itself as a very loud and disagreeable noise. It has furthermore long been recognized that condensers of small capacity and high dielectric strength 40 might be charged to a very high potential by breaking a circuit carrying a unidirectional current flowing in an inductance provided it is possible to give the point of interruption of 45 such circuit a dielectric strength sufficient to withstand said potential within a length of time very short compared to the time required to charge said condenser to said potential, the time required to charge said condenser being equal to one-quarter of the time 50 period of the circuit including said capacity and inductance.

The object of my invention is to provide means for disturbing the electrical equilibrium of a circuit including inductance and capacity more effectively than by the use of the

spark-gap or circuit-controllers which have heretofore been used for this purpose.

In carrying out my invention I may employ a circuit-controller having a plurality of sets of relatively movable electrodes and power-operated means for creating such relative movement, each set of electrodes being so serially subdivided that, without resorting to excessively high peripheral velocities, the path which includes said electrodes may 60 periodically be changed from one which is insulating for very high potentials to one which is substantially metallically-continuous, within a period of time which is sufficiently short to minimize the spark-gap 65 losses aforesaid during the effective radiation of energy from the circuit including said electrodes and which preferably is comparable with the time period of said circuit. I may further employ said circuit-controller, 70 having its electrodes so subdivided and relatively movable, for the purpose of charging the condenser of a sonorous circuit directly from a source of constant and relatively low 75 potential through an inductance, thereby obviating the necessity of employing an induction coil, or an alternating current source with high potential transformer, for this purpose.

My invention may best be understood by 80 having reference to the drawings which accompany and form a part of the present specification and which represent two arrangements of apparatus and systems of circuits embodying my invention. 90

In the drawings, Figure 1 represents partly in diagram and partly in elevation one embodiment of my invention used in a space transmitting system in which a source of alternating current is employed, and Fig. 2 95 represents a similar view of a modification in which a source of direct current is used.

In the figures, V represents an elevated conductor connected to earth at E and including the secondary winding I_2 of a transformer, the primary I_1 of which forms a part of the sonorous circuit including the condenser C and the discharger hereinafter described. It will be understood of course 10 that the sonorous circuit may be associated with said elevated conductor in any suitable manner.

A represents an alternating current generator or other suitable source of alternating current having its leads connected to the key 11

K and the primary I'_1 of the high potential transformer, the secondary I'_2 of which is connected with the sonorous circuit at the points x and y . In the present instance, the 5 circuit-controller or discharger is connected with the sonorous circuit at the points x and y , and consists essentially in a rotating member 2, which I shall term the rotor, carrying the two series of conducting members a b in- 10 sulated from each other and also the two series of conducting members a' b' likewise insulated from each other and arranged diametrically opposite the corresponding members a b . The rotor should be driven at a speed 15 equal to the number of cycles produced by the alternator A and this may be conveniently accomplished by mounting said rotor on the shaft 3 of the alternator.

8' 8" and 9' 9" are rocker arms carrying the 20 rods 10 and 11 respectively, which may be of insulating material and which in turn carry the two series of conducting members 25 c , d , respectively. The rocker arms preferably are arranged to be adjusted about the periphery of the rotor and this may be accomplished by securing them to the collars 5' 6" and 5' 6" supported by the bearings 4' 4" of the shaft 3 and by providing the usual means such as the handles 7' 7" for turning the 30 rocker arms about said bearings and locking the same in adjusted position. As shown, the alternator and the journal 4" may be supported upon a common base 1. The members a b c and d are arranged as shown, so 35 that when one set of moving members, such as that shown at a , passes between a set of stationary members such as that shown at c , the other set of moving members will occupy a corresponding position with respect to the 40 other set of stationary members, so that there will be formed between the points x and y a path of practically-negligible resistance by way of the flexible conductor 12 which connects the stationary members c d 45 which are nearest the alternator.

Assuming that the rotor is rotating in a clockwise direction as viewed from the alternator end, so that the series of members a is approaching the series c , it will be seen that 50 by the proper adjustment of the rocker arms and the proper spacing of the several series, a number of small gaps will be inserted in the path x 12 y , the total dielectric strength of which will prevent the disruptive discharge 55 of the condenser C until the potential of the same has risen to its maximum value. When the potential of the condenser is a maximum, by the adjustments above referred to, the total dielectric strength of said 60 gaps may be made just sufficient to permit the discharge of the condenser across the dis- charger at any given position of the series a and b . As the rotor continues its rotation 65 and the several gaps between the series a and the series c and also between the series

b and series d decrease in length, the said path will become practically metallically continuous so that the disruptive discharge of said condenser is no longer possible. By employing a sufficiently large numer of elements in the several series a b c and d , the disruptive discharge of the condenser can be prevented until the separation between each series of moving members from its coöperating series of stationary members has become 70 very small. If the rotor is given a fairly large peripheral velocity, it will be possible to make the interval of time between the position of the series a , b , at which the first disruptive discharge of the condenser occurs 75 and the position of said series at which the circuit becomes practically metallically-continuous as small as we please, so that such time interval will be comparable with the time of a single oscillation of the sonorous 80 circuit, or, in other words, with the time period of said circuit.

In wireless engineering practice only a small part of the total energy of the wave train is dissipated in the first oscillation and the above means allows the spark-gap to be withdrawn from the circuit during the greater portion of time that radiation is taking place, thereby nearly eliminating spark-gap losses and the disagreeable noise 90 incident to forming large masses of metal vapor. It furthermore prevents the discharge from taking place except when the potential of the condenser is at a maximum 95 in the alternating current cycle thus insuring an equal energy in each succeeding wave train and rendering the sound of the spark "smooth" at the receiving station. By swinging the rocker-arms through an angle 100 of 180 degrees and noticing at what point the potential of the elevated conductor reaches a maximum, this point in the alternating current cycle may be adjusted for. 105

In order to more fully disclose my invention I will now proceed to show by a numerical example using values in common use how the number of electrodes and circumference of the rotor may be determined. 110

Let us assume that the alternating current supply is 60 cycles per second and that the rotor is therefore run at 60 revolutions per second or 3600 to the minute. In order not to get into any construction difficulties due to centrifugal force let us make the rotor only 1 meter in circumference corresponding 115 to about 16 centimeters in radius. This would give a peripheral speed of 60 meters per second. Let us assume the wave length of the wireless station is 1000 meters or 300,000 oscillations per second and that we 120 wish the spark-gap to be short-circuited after the first oscillation or 1/300,000 of a second after the conducting elements of the 125 rotor have approached sufficiently near the rows of brushes to allow a disruptive dis-

charge. With a peripheral speed of 60 meters these elements would move a distance of .2 mm. during this time. We should provide brushes and conducting elements in sufficient number to produce the requisite number of .2 mm. gaps in series to prevent disruptive discharge when the maximum potential on the condensers is applied. The potential necessary to cause a disruptive discharge across .2 mm. of air (Gray, *Physical Review* 1898, Vol. II, p. 199) is about 1000 volts and we should therefore provide for at least 32 gaps of .2 mm. if the maximum potential on the condenser were 32,000 volts. This number of gaps would be obtained by the use of 9 brushes on each rod and 8 conducting elements in each row of the rotor.

It is obvious that should a source of constant high potential be available, the alternating current transformer might be dispensed with together with the necessity of adjusting the rocker-arm to allow discharge of the condenser only at the point of maximum potential during the alternating current cycle. In this case the rotor could be driven at any desired speed by a direct current motor or other means and the speed of rotation would determine the time period between successive wave trains. The source of constant high potential should include some inductance to limit the flow of current during the instant of discharge. It is also obvious to those versed in the art that a portion of the surface of the rotor could be used as a commutator to change condensers from parallel to series connection allowing them to charge in parallel from constant low potential and to discharge in series. It is also obvious that in the case of the rotor revolving synchronously with alternating current, the controlling key may be connected in the high potential circuit as disclosed by me in U. S. Patent 884,070, dated April 7, 1908, so as to allow it to only interrupt the circuit at the instant in the cycle of zero current flow thus preventing wear due to sparking.

Passing now to the second embodiment of my invention, it will be seen that the device shown in Fig. 1 can by the slight modification shown in Fig. 2, be made to open an electric circuit carrying a direct current and insulate the opening to withstand a very high potential within a space of time comparable with 1/300,000 of a second. The modification in question consists in arranging the rotor with conducting members $a' a'$ insulated from each other and extending as shown in the present instance around 315 degrees of arc, and in providing two independent and relatively movable sets of conducting members $c' c'$ and $d' d'$, which perform the function of making a conducting path between the insulated conducting members of the rotor when either set is in contact there with. By varying the angular separation be-

tween the set of electrodes or conducting members $c' d'$, one of which may be mounted on the fixed supports $8' 8'$ and the other on the rocker-arms $9' 9'$, the interval of time during each revolution that the circuit remains open can be varied. This interval would be zero if the brushes were 45 degrees apart and would increase to a maximum as the set of conducting members on the rocker-arm was moved toward the fixed set. 75 With the circuit-controller thus modified it would be possible to operate the wireless transmitting circuit shown in Fig. 1 with a low voltage constant potential source without employing an induction coil. To do this 80 an inductance L should be connected in series with the source of constant potential G and the terminals of this source connected to the points x, y and to these points should also be connected the modified circuit-controller 85 shown in Fig. 2.

The numerical values of various elements of the system should be so adjusted and proportioned that they bear the following relations: Let L_1 be the value of the inductance 90 in the oscillation circuit in henries, C , the value of the capacity in the oscillation circuit in farads, V , the maximum potential in volts to which the condenser in the oscillation circuit is charged, W , the power consumed in 95 watts, in the oscillation circuit, L , the inductance in the constant potential circuit in henries, R , the resistance of the constant potential circuit in ohms, E , the potential of the constant potential circuit in volts, I , the maximum current in the constant potential circuit in amperes, T_1 , the time of one oscillation 100 in seconds, T_2 , the time of one revolution of the rotor in seconds, T_3 , the time during which the circuit through the rotor remains 105 open in seconds, p , the peripheral velocity of the rotor in meters per second, N , the number of gaps in series in the circuit $x 12 y$ or $x 12' y$ through the rotor.

$$T_1 = 2\pi\sqrt{LC} \quad (a) \quad 110$$

$$W = \frac{CV^2}{2T_2} \quad (b) \quad 115$$

$$\frac{1}{2}CV^2 = \frac{1}{2}LI^2 \quad (c)$$

$$I = \frac{E}{R} \left(1 - e^{-\frac{RT_2}{L}} \right) \quad (d) \quad 120$$

$$T_3 = \frac{\pi\sqrt{LC}}{2} \quad (e)$$

$$N = \frac{V}{1000} \quad (f) \quad 125$$

$$P = \frac{.0002}{T_1} \quad (g)$$

Equation (a) determines the time period 130

of the sonorous circuit and therefore the wave-length of the radiated wave.

Equation (b) determines the energy consumed in the sonorous circuit in one second.

Equation (c) shows the relation of the kinetic energy stored in the magnetic field of the inductance or inductances L in the constant potential circuit to the potential energy stored in the condenser C of the oscillation circuit.

Equation (d) determines the value of current in the constant potential circuit with given values of L, E and R, at the end of time T_2 . It will be understood that the time represented by T_2 should be $T_2 - T_3$, but as T_3 is negligibly small compared to T_2 , a sufficiently close approximation is obtained by using the value of T_2 .

Equation (e) shows the relation which is necessary in order that the wave train may be started at the instant when the energy is all stored in the oscillating circuit.

Equation (f) determines the number of gaps in series in the circuit through the rotor.

Equation (g) determines the peripheral speed of the rotor whereby a travel of .2 mm of the conducting elements thereon may cause the discharge path to change from the condition of insulating at the voltage V to perfectly conducting at the end of the first oscillation.

In designing a wireless telegraph transmitting system certain quantities are usually specified in advance. These are wave-length, power absorbed by the oscillation circuit, spark frequency, voltage of constant low potential source, and percentage efficiency of the system, and power factor in the supply source. This determines the numerical value of

$$T_1, W, T_2, E \text{ and } \frac{RT_2}{L}.$$

Certain other quantities are then calculated from engineering experience to give the best results with the quantities specified. These are values of the oscillation condenser, maximum voltage it will have to withstand and value of the oscillation inductance. This determines the value of L_1, C and V . Data necessary to design a proper circuit-controller may be obtained by substituting these values in equations (a), (b), (f), (g). It remains only to design a coil so that the constant potential circuit shall have the correct value of inductance L and resistance R to cause it to deliver energy to the oscillating circuit at the specified rate and within the specified efficiency and power factor.

The efficiency and power factor of the system is fixed by assigning a numerical value to the fraction

$$\frac{RT_2}{L}$$

65

For values of this fraction varying from 1 to .5 the efficiency varies from approximately 50% to 75% respectively and the power factor from approximately 90% to 88% respectively.

It now becomes necessary to determine the values of R and L to give the specified results.

Let

$$k = \frac{RT_2}{L} \quad (h) \quad 70$$

$$m = (1 - e^{-k})^2$$

$$n = 1 - \frac{1}{k}(1.5 - 2e^{-k} + .5e^{-2k}) \quad 80$$

By a simultaneous solution of formulas (b), (c), (d) and (h) it is possible to deduce

$$R = \frac{ME^2}{2Wk} \quad (i) \quad 85$$

$$L = \frac{mE^2T_2}{2Wk^2} \quad (j) \quad 90$$

By applying calculus to equation (d) it is possible to deduce the value of the heat losses in the resistance of the constant low potential circuit

$$i^2 R = \frac{2Wkn}{m} \quad (k) \quad 95$$

also the effective value of the current in this circuit

$$i = \frac{2Wk}{Em} \sqrt{n} \quad (l) \quad 100$$

From equation (k) is obtained the expression

$$\frac{W}{W + i^2 R} = \frac{1}{1 + \frac{2nk}{m}} \quad (m) \quad 105$$

giving the percentage of efficiency of the system.

From equation (l) is obtained the expression

$$\frac{W + i^2 R}{Ei} = \frac{m + 2nk}{2k\sqrt{n}} \quad (n) \quad 115$$

giving the power factor of the supply circuit.

To illustrate the method of calculation more fully I will work out a practical case numerically using values which may be said to be average in working wireless telegraph installations to-day.

The specified quantities are as follows;

$$T_1 = .0000033 \quad 125$$

$$W = 10000 \quad 125$$

$$T_2 = .01 \quad 125$$

$$E = 100 \quad 125$$

$$\frac{RT_2}{L} = k = .5 \text{ (corresponding to 73% efficiency.)} \quad 130$$

The calculated values are as follows:

- C = .1 mfd. = .0000001
 Formula (a) $L_1 = .0000028$
 (b) $V = 45000$
 (c) $T_3 = .0000275$
 (f) $N = 45$
 (g) $p = 60$
 (h) $m = .154$
 (h) $n = .056$
 (i) $R = .154$
 (j) $L = .00308$
 (k) $i^2R = 3650$
 (l) $i = 154$
 (m) Efficiency = 73.3%
 (n) Power factor = 89%

The above values are approximate only within engineering accuracy.

The operation of this system may be explained in the following manner: When the rotor first closes the circuit, current supplied from the constant potential source starts to flow through the inductance L and constantly increases reaching a value I given in equation (d) when the rotor has made almost a complete revolution. At this instant the circuit through the rotor is opened and becomes the electrical equivalent of a closed sonorous circuit of inductance L_1 and capacity C in a condition where the energy $\frac{1}{2} L I^2$ is all stored in the magnetic field. We know from the theory of the sonorous circuit that, after a space of time T_3 equal to one quarter of a single complete oscillation (equation e), this magnetic field will have completely collapsed and all of the energy will be stored in the condenser C and have a value of $\frac{1}{2} C V^2$. At this instant the circuit is again made through the rotor, the energy in the condenser makes an oscillatory discharge through the small inductance L_1 and is dissipated by radiation, while current commences to flow again in the coil and the cycle is complete. The time necessary for radiation to take place is very small compared with the time of one revolution of the rotor and it is advisable to proportion the values of L and C so that T_3 corresponds to only a small angular movement of the rotor. This allows the inductance L_1 to be accumulating energy during the largest possible amount of the total time and renders it possible to use a minimum value of constant electro-motive force for a given number of watts output.

It is obvious from the above that by the use of an inductance, condenser and constant low potential source in combination with a circuit-controller of the nature last described, we may produce high potential disruptive discharges of any desired length. Equations (c) (d) and (e) give us all data required for calculating values necessary to produce any desired value of V. Care should be taken to subdivide the rotor so as to produce

insulating gaps in sufficient number to withstand the desired potential V within a space of time shorter than that given in equation (e). The electrodes between which disruptive discharge is desired should be connected across the condenser C and should have a breakdown potential value anything less than V.

It will be seen that by the employment of my invention as herein set forth I am enabled to produce jump sparks for explosive engines without the use of vibrators or induction coils. Furthermore I am enabled to provide apparatus for use in therapeutic and radio-graphic work wherein the induction coils may be improved and simplified by the omission of the iron core and by a considerable reduction in the amount of wire required. I may also further simplify such induction coil by omitting the usual condenser, because, as pointed out by Wheatstone, if the primary current of an induction coil could be interrupted within a sufficiently short time interval, the use of a condenser might be dispensed with and the secondary potential increased, since it is dependent on the rapidity with which the magnetic field collapses and it is obvious that the above described circuit-controller can be employed for this purpose.

It has long been recognized that an immense advantage would accrue in wireless telegraph engineering if it were possible to completely eliminate the resistance of the spark gap. It has also long been recognized that much greater efficiency could be obtained in converting low potential to high potential by breaking an inductive circuit in which current was flowing if this break could be made with sufficient rapidity to prevent sparking. That neither of these two advantages has been made use of to my knowledge commercially is probably due to the apparent impossibility without resorting to prohibitory velocities of constructing a path which would in a sufficiently short interval of time change between the conditions of perfectly insulating for high potentials and perfectly conducting.

Having shown how the principle of serial subdivision may be made use of to reduce the rapidity of motion necessary to accomplish these results, I claim:

1. A circuit-controller serially connected in a sonorous circuit and having a plurality of sets of serially subdivided electrodes and power-operated means for creating relative movement between the same.

2. A circuit-controller serially connected in a sonorous circuit and having a plurality of sets of serially-subdivided electrodes and means for creating relative movement between the same, the said sets of electrodes being so constructed and arranged that the gaps between the same are practically closed

and said circuit rendered substantially metallically-continuous in an interval of time after the first discharge of the condenser in said circuit sufficiently short to minimize 5 spark-gap losses during the effective radiation of energy from said circuit.

3. A circuit-controller serially connected in a sonorous circuit and having a plurality of sets of serially-subdivided electrodes and 10 means for creating relative movement between the same, the said sets of electrodes being so constructed and arranged that the gaps between the same are practically closed and said circuit rendered substantially metallically-continuous in an interval of time 15 after the first discharge of the condenser in said circuit shorter than the duration of the effective radiation of energy from said circuit.

20 4. A circuit-controller serially connected in a sonorous circuit and having a plurality of sets of serially-subdivided electrodes and means for creating relative movement between the same, the said sets of electrodes 25 being so constructed and arranged that the gaps between the same are practically closed and said circuit rendered substantially metallically-continuous in an interval of time after the first discharge of the condenser in 30 said circuit comparable with the time period of said circuit.

5. A circuit-controller serially connected in a sonorous circuit and having a set of stationary serially-subdivided electrodes, a set 35 of movable serially-subdivided electrodes, and power-operated means for creating relative movement between the same.

6. A circuit-controller serially connected in a sonorous circuit and having a set of stationary serially-subdivided electrodes, a set 40 of movable serially-subdivided electrodes, and means for creating relative movement between the same, said sets of electrodes being so constructed and arranged that the 45 gaps between the same are practically closed and said circuit rendered substantially metallically-continuous in an interval of time after the first discharge of the condenser in said circuit sufficiently short to minimize 50 spark-gap losses during the effective radiation of energy from said circuit.

7. A circuit-controller serially connected in a sonorous circuit and having a set of stationary serially-subdivided electrodes, a set 55 of movable serially-subdivided electrodes, and means for creating relative movement between the same, said sets of electrodes being so constructed and arranged that the gaps between the same are practically closed and 60 said circuit rendered substantially metallically-continuous in an interval of time after the first discharge of the condenser in said circuit shorter than the duration of the effective radiation of energy from said circuit.

65 8. A circuit-controller serially connected

in a sonorous circuit and having a set of stationary serially-subdivided electrodes, a set of movable serially sub-divided electrodes and means for creating relative movement between the same, said sets of electrodes 70 being so constructed and arranged that the gaps between the same are practically closed and said circuit rendered substantially metallically continuous in an interval of time after the first discharge of the condenser in 75 said circuit comparable with the time period of said circuit.

9. A circuit-controller having a plurality of sets of serially - subdivided electrodes, means for creating relative movement be- 80 tween the same, and a circuit including a source of constant potential and an inductance in series with said circuit-controller.

10. A circuit-controller having a plurality of sets of serially - subdivided electrodes, 85 means for creating relative movement between the same, a circuit including a source of constant potential and an inductance in series with said circuit-controller, and a condenser in shunt thereto. 90

11. A circuit-controller having a plurality of sets of serially - subdivided electrodes, means for creating relative movement between the same, a circuit including a source of constant potential and an inductance in 95 series with said circuit-controller, and a condenser in shunt thereto, said sets of electrodes being so constructed and arranged that said circuit is opened sufficiently to withstand the maximum potential to which 100 said condenser is charged within a time shorter than one-quarter of the time period of the circuit including said inductance and said condenser.

12. A circuit-controller having a plurality 105 of sets of serially - subdivided electrodes, means for creating relative movement between the same, a circuit including a source of constant potential and an inductance in series with said circuit-controller, and a condenser and inductance constituting a sonorous circuit in shunt to said circuit-controller, said sets of electrodes being constructed and arranged so that the first mentioned circuit is opened sufficiently to withstand the maxi- 115 mum potential to which said condenser is charged within a time shorter than one-quarter of the time period of the circuit including said condenser and inductances, and so that the said sonorous circuit is prac- 120 tically closed and rendered substantially metallically - continuous in an interval of time after the first desired discharge of the condenser in said sonorous circuit comparable with the time period of said sonorous 125 circuit.

13. A circuit-controller having a set of serially-subdivided electrodes and two sets of alternate serially - subdivided electrodes connected in multiple, a circuit including a 130

source of constant potential and an inductance in series with said circuit-controller, and means for changing the distance between said sets of alternate electrodes.

14. A circuit-controller comprising a rotor having its periphery divided into conducting and insulating sections, a circuit including a source of constant potential and an inductance in series with said circuit-controller, a plurality of serially-subdivided electrodes arranged to make contact with said pe-

riphery, and means for changing the distance between said electrodes so as to alter the ratio of time during which the circuit through said controller is open to the time during which it is closed.

In testimony whereof, I have hereunto subscribed my name this 9th day of Nov. 1908
SEWALL CABOT.
